TIPPING GRAVITY DAVIT FOR LIFEBOATS

Antonino Pampinella, Rome, Italy; vested in the
Alien Property CustodianApplication November 6, 1941, Serial No. 418,094
In Italy January 12, 1941

1 Claim. (Cl. 9—39)

This invention relates to certain improvements in the tipping gravity davits for lifeboats, as disclosed in United States Patent Number 2,305,457, granted December 15, 1942.

One of the objects of this invention is to dispense with the guy ropes for the auxiliary beam of each of the davits, and to dispense with the small removable tackle serving to cause the inward tipping movement of the beam and davit.

Another object of these improvements is to provide a better support for the auxiliary beams when the companion of the ship is sufficiently near the device.

A further object of the invention is to provide a more suitable shape of davit, said shape being such as to cause the boat, when fully withdrawn from the ship's side, to be kept in an upright position and not inclined.

In addition to the main objects as hereinbefore described, this invention provides a lighter davit device, both in the single boat types and in the types for two superposed boats.

In the annexed drawings:

Fig. 1 shows a side view of an adjusting screw system for controlling the auxiliary beam of each elementary davit;

Fig. 2 shows a front view of the system of Fig. 1;

Fig. 3 shows a side view of a different shape of davit, as well as a different arrangement of the screw system;

Fig. 4 shows a side view of a davit formed by tubes located beyond the ends of the boat, instead of being placed laterally of the boat as shown in the previous figures;

Fig. 5 shows a front view of the arrangement of Fig. 4;

Fig. 6 shows a side view of another embodiment, two boats being gravity operated;

Fig. 7 shows a front view of the arrangement of Fig. 6.

It will be understood that the kind, shape and arrangement of the parts which make up the devices according to the improvements herein disclosed may be largely varied, without departing from the scope of the invention, provided that the essential features, as set forth in this specification, are not altered.

The first of the improvements consists in the auxiliary beam 1, for each of the two davits 4 (Fig. 1), adjusted by the screw system 2 which is mounted on a trestle 3 on the deck 13 on which the beams 1 and davits 4 are pivoted on pivots 22. This screw system 2 serves both as a tension and compression member for the beams 1, and

the position of the latter is controlled by screwing or unscrewing the screw. In the embodiment shown in Fig. 1 the normal trim of the davits 4, in which the boat 5 is suspended and partially protrudes from the ship's side 6, is maintained when the screw is fully unscrewed, the latter on the contrary being screwed in to accomplish the inboard tipping movement of beam 1 and davit 4 (dotted lines). The reverse takes place in the embodiments of Figs. 3 and 6, according to which embodiments the boats are fully withdrawn from the ship's side in their normal trim. In the latter instance, the screw has to be unscrewed only when the ship is unfavorably listed. The embodiment shown in Fig. 6 will be dealt with more particularly hereinafter. It will be apparent, therefore, that the use of guy cables for the auxiliary beams 1, as set forth in Patent No. 2,305,457, is no longer required when using the support screw system as hereinbefore disclosed, so that the first of the objects of the invention, as described in the introductory paragraphs of this specification, is fully achieved.

A further improvement according to this invention relates to the shape of the davit 4 (Fig. 25), which has been made sufficiently curved, so that the davit beam unit keeps bending inboard as in the withdrawn boat instance of Fig. 1 (dotted lines). It follows that the boat keeps upright and fully withdrawn from the ship's side 6; the boat may be gravity tipped outboard when the vessel is on even keel, as gravity slightly prevails in this case, viz., by 5 degrees on the suspension point of the davit head with respect to the rotation axis of davit. Should the ship be unfavorably listed, it will be necessary to actuate the screw system 2.

From Fig. 3 it will also be seen that when a companion 7 is available, the trestle 3 of Fig. 1 40 may be dispensed with, and the companion 7 serves as a support for the screw system 2. Moreover, the operating crank of the screw system 2 may be controlled from the deck 13 through suitable transmission members.

A further improvement has been brought about by placing the two elementary davits 4 of the pair beyond the ends of the boat 5 (Figs. 4 and 5). In this case the davit 4 (Fig. 5) is formed by straight tubes which are preferably reduced at their end. As in the previous instances, the beam 1 is still formed by tubes and is provided with an engagement bracket 19 to keep a proper inclination of davits with respect to the beam.

The davits according to the improvements are 55 fitted with gravity saddles 26 (Fig. 4). Two of

such saddles are provided, to keep the boat 5 properly raised at its ends. Each of them comprises a saddle proper 26 and a forked foot 27 the two branches of which are integral with the saddle at the top and are pivotally connected to the deck 13 (Fig. 4) at their lower ends, while a second simple foot 28 (Fig. 4) which is pivoted under the saddle 26, rests on deck 13, where it is stopped by a stop 29. Both the forked and the simple foot are properly held apart with respect to the vertical direction passing through the centre of the saddle, so that on removing the stop 29 the saddle will fall down on the deck 13 owing to its own weight and will leave the boat 5 free to accomplish its gravity tipping movement.

Still another improvement according to this invention relates to the operation of two superposed boats by means of davits formed by tubes of the kind just described. An embodiment of this improvement is shown in Figs. 6 and 7 and according to this embodiment both of the boats are ready to accomplish gravity outboard swinging movements simultaneously. The lower boat 30 rests on the gravity saddles 26 already described, and the upper one 5 rests on the half saddles 31, which are supported by the lower boat 30 and are easily taken away on the falling down of the gravity ones. Each boat is fitted with its own tackle which serves to lower the boats to the sea successively, viz. the lower one 30 first, and the upper one 5 afterwards (Fig. 6, dotted lines).

In the arrangement shown in Figs. 6 and 7, the davits 4 are provided at their bases with forks 4', and the beams 1 at their bases with forks 1', these forks 4' and 1' being mounted on the horizontal pivot 22' so that the longitudinal axes of the davits 4 and beams 1 lie in the same vertical plane. The screw system 2 mounted on the 40

trestle 3 on the companion 7 (Fig. 6) has one end of its rigid rod 2' pivoted on the beam 1 and its other end pivoted on its support, the longitudinal axis of the rod 2' lying in the common plane of the longitudinal axes of the davits 4 and beams 1.

The supporting screw system 2 may be located either in front of the beam 1, as shown in Figs. 4 and 5, or behind it, as shown in Fig. 6. The first arrangement is preferred so as not to encumber the deck 13. In this case, a special transmission rod 20, fitted with a hand crank and supported by a trestle 21 provides for control of the screw system 2.

The screw system 2, when arranged in front of the beam 5, requires a forked support 25 (Figs. 4 and 5), between the two branches of which the davit 4 may swing.

What I claim is:

20 In a tipping davit device for life boats, the combination of a pair of davits mounted on horizontal pivots on the deck of the ship, and spaced from each other along the deck; a pair of beams mounted on horizontal pivots on the deck, the longitudinal axis of each beam lying in the vertical plane in which lies the longitudinal axis of one of said davits; a block and tackle connection between the upper end of each beam and the upper end of its associated davit; a pair of longitudinally adjustable, rigid rods, each having one end mounted on a horizontal pivot on one of the beams adjacent its top, and its other end mounted on a horizontal pivot on the deck, the longitudinal axes of the rods lying in the common planes of the axes of their respective beams and davits; means for adjusting said rods longitudinally; and means for supporting a life boat from said davits.

ANTONINO PAMPINELLA.
